UNITED STATES PATENT OFFICE.

EDWARD WM. EDWARDS, OF CINCINNATI, OHIO.

SHEET-METAL ROOFING.

1,091,049.

Specification of Letters Patent. Patented Mar. 24, 1914.

Application filed January 10, 1914. Serial No. 811,302.

To all whom it may concern:

Be it known that I, EDWARD WM. EDWARDS, a citizen of the United States, and a resident of Cincinnati, county of Hamilton, 5 State of Ohio, have invented certain new and useful Improvements in Sheet-Metal Roofing, of which the following is a full and clear specification, reference being had to the accompanying drawings, in which—

10 Figure 1 is a perspective view showing three adjacent sheets of the metal roofing connected together; Fig. 2 is a transverse vertical section through one of the lock joints; and Fig. 3 is a similar view showing 15 one of the sheets in the position it assumes when bulged or ballooned by high wind.

This invention relates to that type of sheet metal roofing in which large sheet metal sheets are employed, the adjacent overlapping edges of these sheets being detachably locked together in such manner as to prevent ingress of water at any point along the joint, one sample of this type of roofing being shown in patents to H. E. Moomaw, No. 25 1,072,025, dated September 2, 1913, and No. 884,285, dated April 7, 1908.

The object of this invention is to provide a joint which will hold the sheets in interlocking relation under all conditions and 30 also to avoid all sharp bends or folds in the metal, to thereby avoid cracking or peeling of the tin or galvanized coating usually applied to roofing metal sheets.

In the drawings annexed, the numeral 2 35 indicates the main body of the sheet, along one edge of which is formed a ridge 3 and at the other edge a corresponding ridge 4, these two ridges being approximately the same shape in cross section. Outside of the 40 ridge 4 is formed a nailing flange 5 and inside of this ridge 4 is a channel 6, which is formed by folding the metal longitudinally upon itself, this channel facing the adjacent wall of ridge 4. The fold 7 which forms the 45 top of the channel 6 projects to within a short distance of the adjacent wall of the ridge 4. The metal at the two-fold lines 8 and 9 is not folded or bent sharply, these folds being well rounded, the bend in the 50 metal being approximately a semi-circle. The outer wall 10 of the ridge 4 is slightly convex, while the inner wall 11 of this ridge is inclined upwardly and inwardly, so as to partly overhang the throat formed between

the fold 7 and said inclined wall. At the 55 other edge of the sheet the ridge is formed in the same manner as the aforesaid ridge 4, namely, with a convex wall 12 and an inclined wall 13, and outside of the wall 13, the extreme longitudinal edge of the sheet, the 60 sheet is formed into a curved flange 14.

It will be observed that to interlock the edges of the sheets the flange 14 is inserted in the channel 6 and the walls 13 and 12 fit down closely over the walls 11 and 10 of the 65 ridge on the other sheet. At the juncture of the lip or flange 14 and the wall 13, the fold is well rounded as is likewise the fold at the base of the wall 11 of the companion ridge, so that when the parts are in position, these 70 corner folds fit snugly together.

It will be observed that contraction of the sheets under the heat of the sun will cause the inclined walls of the ridges to tightly interlock, by reason of the inclination of 75 the walls, the stronger the tension of the sheet the greater being the interlocking action. Expansion of the sheets will simply cause the walls 13 and 11 to slightly separate, but will not permit the parts to be disconnected. Should high winds balloon or bulge any one of the sheets of the roofing, it will be observed from Fig. 3 that the wall 13 of the outer ridge will be thrown up into abutting relation with the overhanging wall 85 11 of the under ridge, while the flange or lip 14 will engage under the rounded nose of the lock fold 7, thereby absolutely locking the edge of the sheet against withdrawal from the channel. This is a very important 90 feature of my device, and its importance will be understood when it is kept in mind that the roofing sheets are made quite large and are, therefore, capable of considerable of a ballooning or bulging action in case high 95 winds get under the sheets. It will be observed also that with my construction I avoid all sharp bends along the fold lines and thus avoid the cracking or peeling of the surfacing metal, the result of this being that 100 deterioration of the sheets by reason of rust will be greatly postponed.

Having thus described my invention, what I claim is:

A sheet metal roofing plate having a ridge 105 parallel with and a short distance from each of its side edges, these ridges being approximately the same shape in cross section, the

outer wall of one of the ridges being inclined toward the adjacent edge of the sheet and the inner wall of the other ridge being inclined away from the edge of the sheet, the sheet at a point close to the last named inclined ridge wall being longitudinally folded upon itself to form a channel facing said inclined wall, the folded part of the

metal extending close to said inclined wall, for the purposes set forth. 10

In testimony whereof I hereunto affix my signature in the presence of two witnesses.

EDWARD WM. EDWARDS.
